UNITED STATES PATENT OFFICE.

CHARLES SMITH, OF TOPEKA, KANSAS.

DERRICK.

No. 921,295.

Specification of Letters Patent.

Patented May 11, 1909.

Application filed June 23, 1908. Serial No. 440,005.

To all whom it may concern:

Be it known that I, CHARLES SMITH, a citizen of the United States, residing at Topeka, in the county of Shawnee and State of Kansas, have invented a new and useful Derrick, of which the following is a specification.

This invention relates to cranes or derricks, and more especially to derricks of that general type employed on railway cars for wrecking and other purposes.

One of the principal objects of the invention is to provide a novel form of derrick that is so mounted on a turn table or revoluble platform as to permit adjustment of the derrick standard and boom to position at both sides and in front or rear of the car or other support, and which may be used without the employment of the usual bracing jacks that are commonly employed for the purpose of preventing overturning in car derricks.

A still further object of the invention is to provide a device of this class in which all of the working parts, including the boiler, hoisting engines, winding drums and derrick are mounted on a single revoluble platform, the various parts being so disposed that the weight of the boiler and engines will effectively counter-balance any ordinary load which may be imposed on the derrick.

A still further object of the invention is to provide a device of this class in which a derrick may be turned to any angle whether idle or loaded.

With these and other objects in view, as will more fully hereinafter appear, the invention consists in certain novel features of construction and arrangement of parts, hereinafter fully described, illustrated in the accompanying drawings, and particularly pointed out in the appended claims, it being understood that various changes in the form, proportions, size and minor details of the structure may be made without departing from the spirit or sacrificing any of the advantages of the invention.

In the accompanying drawings: Figure 1 is a side elevation, partly in section, of a derrick constructed in accordance with the invention. Fig. 2 is a plan view of the same, the boiler shell being shown in section.

Similar numerals of reference are employed to indicate corresponding parts throughout the several figures of the drawings.

The derrick is mounted on any suitable support, such as A which may be in the form

of a railway car, float or other structure. On this support is arranged a sole plate 10 and on top of the sole plate is arranged a base plate 11 of the derrick.

The base plate 11 carries a depending pin 12 that fits within a suitably shaped socket formed in the sole plate at the center of a stationary gear or angular rack 13 that is formed integral with or is secured to the sole plate, and intermeshing with this stationary gear is a pinion 14, that is carried by a vertically disposed shaft 15 mounted on a suitable bearing 16 and provided at its upper end with a hand wheel 17 which may be turned for the purpose of revolving the base plate and all of the parts carried thereby, the construction being such that the base plate and the derrick are free to make a complete revolution.

In the adjacent faces of the base and sole plates are formed annular races for the reception of bearing balls 18, this ball bearing permitting free turning of the derrick when loaded.

Arranged at the rear end of the base plate is a boiler 20 and a pair of reciprocating engines 21, the pistons of which are connected in the usual manner to the opposite ends of a shaft 22 that is mounted in suitable bearings in a pair of cheek plates or standards 23 that are arranged near the opposite sides of the base plate in advance of the boiler.

The shaft 22 is geared to hoisting drums 28 and 29 arranged to receive hoisting cables 30 and 31, which operate in connection with blocks 37, carried by a derrick standard 36.

The derrick standard is mounted at the front end of the base plate, and the derrick, hoisting drums, engines and boiler are so relatively positioned with respect to the central pin 12 that the weight of the boom and engines will counter-balance any ordinary load hoisted by the derrick, so that in case the base plate is turned to such position that its longitudinal axis is at a right angle to the length of the car or other support, it will be unnecessary to employ bracing jacks or the like at the sides of the car or under the derrick base.

What is claimed is:

In a derrick, a sole plate having a circular raised portion on its upper surface, said raised portion being provided with a central opening, a rack in the periphery of said raised portion, a base plate having a depending pivot pin seating in the aforesaid central

opening, a shaft carried by the base plate, a pinion on the shaft meshing with the rack, a depending annular flange on the base plate surrounding the raised portion of the sole plate and concentric with the pivot, and an anti-friction bearing between said flange and the top of the sole plate.

In testimony that I claim the foregoing as my own, I have hereto affixed my signature in the presence of two witnesses.

CHARLES SMITH
